CLAIM

The ornamental design for a gaming machine, as shown and described.

DESCRIPTION

FIG. 1 is a front perspective view of a gaming machine showing our design according to a first embodiment;
 FIG. 2 is a front elevation view thereof;
 FIG. 3 is a rear elevation view thereof;
 FIG. 4 is a top plan view thereof;
 FIG. 5 is a bottom plan view thereof;
 FIG. 6 is a left side elevation view thereof;
 FIG. 7 is a right side elevation view thereof;
 FIG. 8 is a front perspective view of a gaming machine showing our design according to a second embodiment;
 FIG. 9 is a front elevation view thereof;
 FIG. 10 is a rear elevation view thereof;
 FIG. 11 is a top plan view thereof;
 FIG. 12 is a bottom plan view thereof;
 FIG. 13 is a left side elevation view thereof;
 FIG. 14 is a right side elevation view thereof;
 FIG. 15 is a front perspective view of a gaming machine showing our design according to a third embodiment;
 FIG. 16 is a front elevation view thereof;
 FIG. 17 is a rear elevation view thereof;
 FIG. 18 is a top plan view thereof;
 FIG. 19 is a bottom plan view thereof;
 FIG. 20 is a left side elevation view thereof;
 FIG. 21 is a right side elevation view thereof;
 FIG. 22 is a front perspective view of a gaming machine showing our design according to a fourth embodiment;
 FIG. 23 is a front elevation view thereof;
 FIG. 24 is a rear elevation view thereof;
 FIG. 25 is a top plan view thereof;
 FIG. 26 is a bottom plan view thereof;
 FIG. 27 is a left side elevation view thereof;
 FIG. 28 is a right side elevation view thereof;
 FIG. 29 is a front perspective view of a gaming machine showing our design according to a fifth embodiment;
 FIG. 30 is a front elevation view thereof;
 FIG. 31 is a rear elevation view thereof;
 FIG. 32 is a top plan view thereof;
 FIG. 33 is a bottom plan view thereof;
 FIG. 34 is a left side elevation view thereof;

FIG. 35 is a right side elevation view thereof;
 FIG. 36 is a front perspective view of a gaming machine showing our design according to a sixth embodiment;
 FIG. 37 is a front elevation view thereof;
 FIG. 38 is a rear elevation view thereof;
 FIG. 39 is a top plan view thereof;
 FIG. 40 is a bottom plan view thereof;
 FIG. 41 is a left side elevation view thereof;
 FIG. 42 is a right side elevation view thereof;
 FIG. 43 is a front perspective view of a gaming machine showing our design according to a seventh embodiment;
 FIG. 44 is a front elevation view thereof;
 FIG. 45 is a rear elevation view thereof;
 FIG. 46 is a top plan view thereof;
 FIG. 47 is a bottom plan view thereof;
 FIG. 48 is a left side elevation view thereof;
 FIG. 49 is a right side elevation view thereof;
 FIG. 50 is a front perspective view of a gaming machine showing our design according to an eighth embodiment;
 FIG. 51 is a front elevation view thereof;
 FIG. 52 is a rear elevation view thereof;
 FIG. 53 is a top plan view thereof;
 FIG. 54 is a bottom plan view thereof;
 FIG. 55 is a left side elevation view thereof;
 FIG. 56 is a right side elevation view thereof;
 FIG. 57 is a front perspective view of a gaming machine showing our design according to a ninth embodiment;
 FIG. 58 is a front elevation view thereof;
 FIG. 59 is a rear elevation view thereof;
 FIG. 60 is a top plan view thereof;
 FIG. 61 is a bottom plan view thereof;
 FIG. 62 is a left side elevation view thereof;
 FIG. 63 is a right side elevation view thereof;
 FIG. 64 is a front perspective view of a gaming machine showing our design according to a tenth embodiment;
 FIG. 65 is a front elevation view thereof;
 FIG. 66 is a rear elevation view thereof;
 FIG. 67 is a top plan view thereof;
 FIG. 68 is a bottom plan view thereof;
 FIG. 69 is a left side elevation view thereof;
 FIG. 70 is a right side elevation view thereof;
 FIG. 71 is a front perspective view of a gaming machine showing our design according to an eleventh embodiment;
 FIG. 72 is a front elevation view thereof;
 FIG. 73 is a rear elevation view thereof;
 FIG. 74 is a top plan view thereof;
 FIG. 75 is a bottom plan view thereof;
 FIG. 76 is a left side elevation view thereof;
 FIG. 77 is a right side elevation view thereof;
 FIG. 78 is a front perspective view of a gaming machine showing our design according to a twelfth embodiment;
 FIG. 79 is a front elevation view thereof;
 FIG. 80 is a rear elevation view thereof;
 FIG. 81 is a top plan view thereof;
 FIG. 82 is a bottom plan view thereof;
 FIG. 83 is a left side elevation view thereof; and,
 FIG. 84 is a right side elevation view thereof.

The dashed broken lines in the figures illustrate portions of the gaming machine that form no part of the claimed design.
